UNITED STATES PATENT OFFICE

FLOYD R. WOOD, OF GRAND RAPIDS, MICHIGAN

ENGINE STARTING DEVICE

Application filed December 10, 1930. Serial No. 501,230.

This invention pertains to a device adapted to be applied to the ignition system of an internal combustion engine and more particularly to an attachment adapted to be fastened to one contact of the timing unit of the usual automobile engine whereby the timer may be made to operate even though the ignition switch is in a locked position.

One manner of locking automobiles against unauthorized movement is to lock the ignition switch so that the terminal which leads therefrom to the contact screw, inside of the distributor cover, and which carries a positive current, is shorted to the frame of the automobile whereby it is grounded or in other words whereby it is negative as regards its phase of electricity.

It is often desirable, particularly for garage men who desire to rearrange locked automobiles inside of their garage, to be able to quickly start the engine and hence quickly and expediently move the car to its chosen position. Also my device is usual in connection with parking lots whereby locked parked cars may be conveniently moved.

My aim is to construct and inventively create a small attachment which may be easily applied to the distributor of the locked car and also to any wire on the opposite side of the coil unit with respect to the battery and which carries the positive phase of the battery current whereby the timing device will operate in the usual manner thus giving the interruptions in the primary circuit, these interruptions being necessary in order to generate the high tension secondary current which goes to the spark plugs of an internal combustion engine in a manner well known to those cognizant in this art.

As a matter of fact I also utilize the wire which leads from the ignition switch to the contact point and which grounds the contact point when the ignition switch is in locked position. I do this by connecting a wire onto the U-shaped member which supports my device in position and this wire passes through a condenser, the other side of the condenser being connected to the auxiliary contact point as will later be fully set forth.

Other objects will appear, or become apparent or obvious and will suggest themselves during the description of the device shown in the accompanying drawings, in which,

Fig. 1 is a perspective view of an engine block, cowl, coil, distributor and terminal box of a usual automobile.

Fig. 2 is a top view of the usual timer therefor, the distributor cap being removed.

Fig. 3 is a view similar to Fig. 2 but showing my invention applied thereto.

Fig. 4 is a perspective view of my invention, showing the base unit, condenser and spring clip, and

Fig. 5 is a schematic illustration showing the usual electrical circuit of the internal combustion engine in full lines and the electrical circuit of my attachment in dotted lines.

Similar numerals refer to similar parts throughout the several views.

Referring particularly to Fig. 1, 10 indicates the engine block, having the usual spark plugs 11, distributor and timing unit 12, with the high tension wire 13 leading therefrom, 14 the coil, 15 the terminal box and 16 the cowl of the automobile.

As is shown in Fig. 5, the coil 14 is connected to a battery 17, grounded as shown, an ignition switch 18, grounded at 19 as shown, this being done when the ignition switch is locked, or else the ignition switch may be turned to an operative position, as indicated by the arrow thus permitting the low tension current a continuous path through the primary of the coil 14 when the breaker is in its closed position. A condenser 20 shunted across the breaker points in order to minimize the arcing thereof.

As shown in Fig. 2 the timer comprises a breaker arm 25 held against the contact screw 27 by means of the spring 26. The contact screw is threadably engaged in the clamp 28 and a contact lock screw 29 holds the contact screw in position so that its contact point 30 abuts against the contact point 31 on the breaker arm. A vertical shaft, driven from the engine shaft and in proper time therewith, has the usual cams 32 pro-

truding therefrom, these cams coacting with the breaker arm to separate the contact points and thus operate the coil so that a surge of electricity of high voltage passes through the distributor, not shown, to the spark plugs.

Referring now to Figs. 3 and 4, 40 indicates a base element, formed of insulating material, having a member 41 held thereto by means of a rivet 42. This member has an arm 43 extending therefrom and an auxiliary contact point 44 is mounted thereon. An insulating strip 45 is placed immediately back of the strip 43 and serves to insulate the auxiliary contact point from the contact point 30.

A conducting wire 46 leads from the member 41 to a spring clip 47, this clip being rigidly connected to the condenser unit 48, the condensing unit serving as a handle for the spring clip in addition to its usual function. The spring clip 47 is adapted to be clamped on the wire connecting the coil and ignition switch. A wire 49 leads from the other end of the condenser back to the U-shaped member 50. The member 50 is fastened in place under the contact locking screw 29 and not only serves as a support for the base element 40 and its appurtenances but also serves to ground the wire 49 leading from the condenser.

The operation is readily understood.

When an automobile ignition switch has been locked in the usual manner the several electrical units are connected as is shown in Fig. 5 and hence the contact point 30 is grounded. Thus, obviously, the engine will not start as no spark can be created by the electrical units. Now, to apply my invention or auxiliary contact device, the distributor cap is removed the contact locking screw 29 loosened and the contact screw 25 properly rotated so as to increase the distance between the contact points a considerable amount. Next, the U-shaped member 50, rigid with the base element 40, is slid under the head of the screw 29 until its auxiliary contact point 44 is properly positioned relative to the contact point 31 on the breaker arm and then the contact locking screw 29 is tightened.

The spring clip 47 is now fastened to a proper positive wire and the distributor cap is now placed back in position. Now, as has previously been explained the operation of the electrical system of the car will once more be ready for proper operation and hence the car may be driven as desired.

While I have described a complete embodiment of my invention I do not wish to be limited to the particular construction shown, my invention being in fact limited solely by the attached claims.

I claim:

65 1. In an electrical timing arrangement

having a grounded breaker arm, a contact point adapted to be operatively associated therewith and means to adjustably support the contact point in operative or inoperative position, the combination of a support, means adapted to mount the support upon the aforesaid means which supports the contact point, a metal arm extending from the support and adapted to lie in front of the contact point when the same is in inoperative position, said metal arm being insulated from the supporting means, an auxiliary contact point affixed to the metal arm and electrical conducting means fastened to the metal arm. 70

2. In an electrical timing arrangement 75 having a grounded breaker arm, a contact point adapted to be operatively associated therewith, means to adjustably support the contact point in operative or inoperative position, and means to ground the contact point as desired, the combination of a support, means adapted to mount the support upon the aforesaid means which supports the contact point, a metal arm extending from the support and adapted to lie in front 80

of the contact point when the same is in inoperative position, said metal arm being insulated from the supporting means, an auxiliary contact point affixed to the metal arm and electrical conducting means fastened to the metal arm, means for supplying a positive phase of electricity thereto, a condenser, means for connecting one side of the condenser to the first mentioned contact point when it is grounded and means for electrically 85 connecting the other side of the condenser to the auxiliary contact point. 90

3. An auxiliary contact point arrangement 95 comprising a base plate consisting of insulating material, a metal arm fastened to the base plate and extending therefrom, a contact point mounted upon said arm, a U-shaped clamping member extending from the base plate substantially parallel to the aforesaid arm and electricity conducting means 100 fastened to and extending from the metal arm whereby the contact point may be energized by supplying a current to said conducting means. 105

4. In a timer for the usual internal combustion engine having a breaker arm, a contact screw adapted to be cooperatively associated therewith and means for maintaining the contact screw in place the combination of an auxiliary contact point, means to mount the contact point in front of the end of the contact screw and slightly spaced therefrom whereby the same is insulated 110 from the contact screw, said last mentioned means being cooperatively associated with the first mentioned means. 115

5. An article of manufacture comprising a base, a contact point thereon, conducting means connected to and leading from said 120

contact point and means to clamp the base in position.

6. An article of manufacture comprising a base, a contact point thereon, a spring clip, 5 conducting means connected to and leading from said contact point to said spring clip, means to clamp the base in position, a condenser and means for placing the condenser in series between the spring clip and the 10 base clamping means.

7. An article of manufacture comprising a base formed of insulating material, a contact point thereon, conducting means leading from said contact point, a clip on the end of 15 said conducting means, and means on said base and extending therefrom whereby the base may be clamped in fixed position.

8. In a device of the character described, 20 a base plate formed of insulating material, a metal arm supported thereby and extending therefrom, a contact point on one face of the arm, an insulating medium on the other face of the arm, a U-shaped clamping member rigid with the base plate and flexible conducting means leading from the said metal arm. 25

In testimony whereof I affix my signature.
FLOYD R. WOOD.
